ADJUSTABLE BEARING PLATE FOR WIRE LINE PUMPING JACKS

Filed March 15, 1927

Patented Dec. 6, 1927.

1,652,048

UNITED STATES PATENT OFFICE.

JAMES R. ROBB, OF OILTON, OKLAHOMA.

ADJUSTABLE BEARING PLATE FOR WIRE-LINE PUMPING JACKS.

Application filed March 15, 1927. Serial No. 175,617.

This invention relates to adjustable bearing plates for wire line pumping jacks.

An important object of the invention is to provide a device which will permit the saddle forming the pivot for the pumping jack structure to be adjusted toward or away from the well and likewise to be rotatably adjusted as to its angle, so that it will be arranged transversely of a radius intersecting the axis 10 of the well, regardless of improper application of the base proper to the sills upon which it is mounted.

A still further object of the invention is to provide a device of this character which 15 may be relatively cheaply produced and is readily applied.

These and other objects I attain by the construction shown in the accompanying drawings, wherein for the purpose of illustration is shown a preferred embodiment of 20 my invention and wherein:—

Figure 1 is a side elevation of a pumping jack mounted upon an adjustable bearing plate constructed in accordance with my invention;

Figure 2 is a plan view of the bearing plate;

Figure 3 is a section on the line 3—3 of Figure 2;

Figure 4 is a section on the line 4—4 of Figure 2.

Referring now more particularly to the drawings, the numeral 10 generally designates a wire line pumping jack and 11 the saddle thereof, which comprises a shaft extending transversely of the general plane of the jack structure. In accordance with my invention, these saddles are usually pivoted upon base castings (not herein illustrated) 40 which are mounted upon sills 12 arranged adjacent to and extending radially from the well casing 13.

In accordance with my invention, I provide a cast base 14, at present illustrated as 45 provided with apertured ears 15 through which securing elements may be extended to attach the same to the sills 12. This base is arranged with its longitudinal axis approximately transverse to a radius of the well casing 13 and is provided centrally with a longitudinally extending slot 16. Adjacent each end, the base has formed therethrough a longitudinally extending slot 17, the lower end of which opens into a recess 18, the upper wall of which is provided with transverse corrugations 19. Arranged within each re-

cess is a block 20, which fits between the side walls of the recess and has its upper face corrugated for coaction with the corrugations 19 of the upper recess wall. These 60 plates 20 constitute washer plates and are apertured for the passage of bolts 21 and provided with recesses 22 in their lower faces receiving and fitting the heads of the bolts to prevent rotation thereof.

The upper surface of the base is flat and has seated thereon a saddle casting 23, which has a lower surface flat, with the exception of a centrally located circular lug 24, the diameter of which is the same as the width of the slot 16 of the base. This lug extends into the base and serves not only as a pivot about which the saddle casting may be rotated, but also an additional function, which will hereinafter become apparent. The ends of the 70 saddle casting 23 have arcuate slots 25 curved with the lug 24 as a center, and of a size to permit passage of the securing elements 21. The upper face of the casting 23 adjacent the arcuate slots is provided with corrugations 26 transverse to the slots 25 and adapted for coaction with corrugations upon the under surface of washer plates 27 through which the securing elements 21 likewise extend and against which the nuts 28 of the 75 securing elements abut.

Immediately inwardly of the slots, the saddle casting is provided with opposed pairs of transversely spaced lugs 29 and 30, the lugs 29 being relatively large and disposed 80 at that side of the saddle casting from which the wire line 31 of the pumping apparatus exerts its pull, while the lugs 30 are relatively small and merely serve to prevent the saddle 11 from jumping forward or toward the 90 well. The lugs 29 and 30 of each pair are connected at their outer faces by a web 31, which engages the corresponding end of the saddle and serves to prevent movement thereof longitudinally of the saddle casting. Between the pairs of lugs 29 and 30, the upper 95 face of the saddle casting is grooved to receive and fit the saddle, as at 32.

In applying the base plate, it is applied to the sills 12 with its center as nearly as 100 possible in a direct line between the pump rods of the well casing 13 and the point from which the wire line 31 is operated. The saddle casting 23 is then seated thereon and the securing elements 21 left loose until the 105 jack has been positioned. By placing the wire line under strain which tends to lift

- the pump rods, this jack will naturally assume a position where no side strains are applied thereto. In order to accomplish this, it may be necessary that the saddle casting 5 rotate about its lug 24 as a pivot and also shift longitudinally with respect to the base casting. Just as soon as the jack has assumed its proper position, the securing elements may be tightened and the saddle casting 10 will be firmly held against displacement. The lug 24, during operation of the pump, serves to prevent the strain exerted by the wire line from being placed directly against the securing elements 21. The larger lugs 15 29 of each pair are preferably each formed with a lubricant receiving pocket 33 communicating with the saddle confronting face of the lug. These pockets may be provided with hinged covers 34.
- 20 Since the construction hereinbefore set forth is capable of a certain range of change and modification without materially departing from the spirit of the invention, I do not limit myself to such specific structure 25 except as hereinafter claimed.
- I claim:—
1. In a saddle mounting for the wire line pumping jacks of oil well pumps, a base adapted to be secured to a suitable support 30 and having a longitudinally extending slot, a saddle casting having a circular lug fitting in the slot, the base having adjacent each end thereof a longitudinally extending slot, the saddle casting having adjacent each 35 end thereof an arcuate slot and a securing element extending through each arcuate slot and the corresponding longitudinal slot of the base for securing said saddle casting in adjusted position.
  - 40 2. In a saddle mounting for the wire line pumping jacks of oil well pumps, a base adapted to be secured to a suitable support and having a longitudinally extending slot, a saddle casting having a circular lug fitting 45 in the slot, the base having adjacent each end thereof a longitudinally extending slot, the saddle casting having adjacent each end 50 thereof an arcuate slot, a securing element extending through each arcuate slot and the corresponding longitudinal slot of the base for securing said saddle casting in adjusted 55 position, remote faces of the base and saddle casting having adjacent said slots corrugations extending transversely of the slot and washer plates upon the securing 60 elements having corrugations for coaction with the corrugations of the base and saddle casting.
  3. In a saddle mounting for the wire line 65 pumping jacks of oil well pumps, a base

adapted to be secured to a suitable support and having a longitudinally extending slot, a saddle casting having a circular lug fitting in the slot, the base having adjacent each end thereof a longitudinally extending 65 slot, the saddle casting having adjacent each end thereof an arcuate slot, a securing element extending through each arcuate slot and the corresponding longitudinal slot of the base for securing said saddle casting in 70 adjusted position, the upper face of the saddle casting having a longitudinally extending groove for the reception of the saddle and lugs extending upwardly from the face 75 of the saddle casting at opposite sides of the ends of said groove.

4. In a saddle mounting for the wire line pumping jacks of oil well pumps, a base adapted to be secured to a suitable support and having a longitudinally extending slot, 80 a saddle casting having a circular lug fitting in the slot, the base having adjacent each end thereof a longitudinally extending slot, the saddle casting having adjacent each end thereof an arcuate slot, a securing element 85 extending through each arcuate slot and the corresponding longitudinal slot of the base for securing said saddle casting in adjusted position, the upper face of the saddle casting having a longitudinally extending 90 groove for the reception of the saddle and lugs extending upwardly from the face of the saddle casting at opposite sides of the ends of said groove, the faces of said lugs adjacent the ends of the saddle casting being 95 connected by a web.

5. In a saddle mounting for the wire line pumping jacks of oil well pumps, a base adapted to be secured to a suitable support and having a longitudinally extending slot, 100 a saddle casting having a circular lug fitting in the slot, the base having adjacent each end thereof a longitudinally extending slot, the saddle casting having adjacent each end 105 thereof an arcuate slot, a securing element extending through each arcuate slot and the corresponding longitudinal slot of the base for securing said saddle casting in adjusted position, the upper face of the saddle casting having a longitudinally extending groove for 110 the reception of the saddle and lugs extending upwardly from the face of the saddle casting at opposite sides of the ends of said groove, the lugs at one side of the groove being relatively large and formed with lubricant reservoirs.

In testimony whereof I hereunto affix my signature.

JAMES R. ROBB.
